UNITED STATES PATENT OFFICE.

MICHAEL C. RYAN, OF OSWEGO, NEW YORK.

AWNING.

SPECIFICATION forming part of Letters Patent No. 634,478, dated October 10, 1899.

Application filed April 30, 1898. Serial No. 679,311. (No model.)

To all whom it may concern:

Be it known that I, MICHAEL C. RYAN, of Oswego, in the county of Oswego, in the State of New York, have invented new and useful 5 Improvements in Awnings, of which the following, taken in connection with the accompanying drawings, is a full, clear, and exact description.

This invention has special reference to the 10 species of awning in which the awning-cloth is gathered in folds by means of ropes connected at one end to the free end of the awning and at the opposite end to spools secured to a revoluble shaft extending lengthwise of 15 the awning immediately under the top portion thereof.

The object of the invention is to reduce to a minimum the length, friction, and wear of the hoisting-ropes and to dispense with the 20 use of sheaves or pulleys hung loosely on the building or pivoted to separate supports, which sheaves or pulleys are liable to become detached or otherwise disabled, and thus ruin the efficiency of the entire system; and the 25 object of the invention is, furthermore, to prevent entanglement of the awning-cloth with the aforesaid shaft in the operation of raising and gathering in folds the said cloth; and to that end the invention consists in the im- 30 proved construction and combination of parts hereinafter described, and set forth in the claim.

In the annexed drawings, Figure 1 is a front view of an awning-frame equipped with my 35 invention, the awning-cloth being omitted to better illustrate the invention. Fig. 2 is a vertical transverse section on line W W in Fig. 1 with the awning-cloth attached. Figs. 3, 4, and 5 are enlarged transverse sectional 40 views respectively on lines X X, Y Y, and Z Z in Fig. 1; and Fig. 6 illustrates a modification of the means for facilitating the operation of raising the awning.

Similar letters of reference indicate corresponding parts.

A represents the awning-cloth or awning proper, which is suspended in the usual manner from hooks or other suitable devices fastened to the building, as shown at a. To the 45 lower or free portion of the awning is fastened the usual frame b, which holds the awn-

ing taut transversely and is pivoted to brackets d d, attached to the building to sustain the awning laterally, as more clearly shown in Fig. 2 of the drawings. Beneath the fastening devices a a of the upper end of the awning-cloth is a revoluble shaft e, extending across the exterior of the building and journaled in suitable bearings e', firmly secured to the building. To the shaft are adjustably 60 fastened suitable drums or spools f f, upon each of which is wound a rope c, which extends from thence directly to the frame b, and thus dispenses with loose sheaves or pulleys and reduces to a minimum the length, friction, and wear of the ropes.

Various means may be employed for turning the shaft e to cause the wires or ropes c c to be wound and unwound on the spools f f, and thereby raise and lower the awning. I 70 prefer to employ for that purpose a chain-wheel h, fastened to the shaft e, and a chain h', suspended therefrom to be operated by hand and to be permitted free movement when released from the hand.

To facilitate the operation of turning the shaft e, I employ a suitable counterpoise, which may consist either of a spiral spring i, as shown in Figs. 1 and 3, or of a weight j, as represented in Fig. 6 of the drawings. The 80 spring i surrounds the shaft and is suitably fastened at one end to the building and connected at the opposite end to a collar l, which is adjustably mounted on the shaft to permit the tension of the spring to be increased or 85 diminished, as may be desired, to facilitate the aforesaid operation. When the weight j is preferred, I attach said weight to the free end of a chain or rope j', attached to a drum t, secured to the shaft e.

To lock the awning in its raised position, I employ a suitable detent adapted to engage and release the shaft. I preferably form said detent of a wheel D, fastened to the shaft e and provided with notches n n in its periphery, and a dog o, pivoted to the bracket o', engages said notches, as illustrated in Fig. 5 of the drawings. A rod o' is connected to said dog for throwing it out of engagement when desired.

It will be observed that by turning the shaft e the wires or ropes c are wound or unwound

on the spools *ff* and cause the awning to be raised or lowered, as may be desired, and this operation is materially facilitated by the use of either the spring *i* or weight *j*. These counterpoises may be so adjusted as to cause them to automatically raise the awning as soon as the dog *o* is thrown out of engagement with the wheel *D*.

It will be noted that my invention dispenses with the usual pulleys or sheaves, which are liable to be torn from their fastenings, and thus deprive the awning of its necessary support, and also removes the awning from its sheltering position without winding the awning on the shaft.

To effectually maintain the awning-cloth out of contact with the shaft *e* and free from liability of becoming entangled therewith, I place over said shaft a suitable guard *s*, upon the exterior of which the awning-cloth is

gathered in folds in the operation of raising the awning.

What I claim as my invention is—

The combination, with the awning-cloth attached at its upper edge to stationary fastenings on the building, the frame pivoted to the building and connected to the lower end of said cloth, mechanism for raising said frame, the revoluble shaft beneath said upper fastenings, and spools attached to said shaft, of hoisting-ropes extending from said spools directly to the aforesaid pivoted frame, and a guard disposed over the aforesaid shaft to receive upon its exterior the folds of the raised awning-cloth substantially as set forth. 35

MICHAEL C. RYAN.
